UNITED STATES PATENT OFFICE.

EDWARD GIBSON, OF JERSEY CITY, NEW JERSEY.

STEAM-BLOWER.

SPECIFICATION forming part of Letters Patent No. 717,566, dated January 6, 1903.

Application filed June 17, 1901. Serial No. 64,841. (No model.)

To all whom it may concern:

Be it known that I, EDWARD GIBSON, a citizen of the United States, residing in Jersey City, in the county of Hudson, in the State of New Jersey, have invented a certain new and useful Improvement in Steam-Blowers, of which the following is a specification.

It has long been known that fires can be successfully blown by driving air into the ash-pit by the frictional action of strong currents of steam. Steam at full pressure is taken from the boiler and allowed to escape with great force through small apertures in pipes arranged in a passage through which air is introduced into the space under the grate. Properly conditioned a large quantity of air is thus introduced at a pressure sufficiently high to materially increase the upflow through the mass of burning fuel. The steam on reaching the fire assumes a dry and superheated condition, and after this condition is attained it is believed to contribute much to the clearness and vigor of the combustion. My blower is of such class. Among other modes of arranging such perforated pipes has been the placing them in an aperture in the door and making them turn therewith in the opening and closing of the door. I do this. I have devised simple means for drying the steam thus used before it is carried into the ash-pit, thus attaining economy by bringing some of the spent heat back to the fire, and this without risk of ever too much superheating it. This allows the maintaining of a perfect swinging joint in the line of the door-hinges. I have discovered that by making the entire blowing means for a door in one continuous length of pipe I can without requiring any other than the ordinary door-opening blow more economically and efficiently than by any construction of such device known to me and provide for easily cleaning the interior of the coils when required. The pipe in the door is bent to an approximate volute, with its center carried inward, making it tapered. I will refer to it sometimes as "snail-formed." I vary from the simple snail form in three important respects: First, the coil is nearly elliptical, matching to a casing put into the ordinary door-opening; second, the inner end departs from the snail form entirely and stands at right an-

gles to the plane of the door, and, third, such end has a cap which may be removed to blow through for cleaning. This cap, like the entire face of the coil which is presented toward the interior of the ash-pit, is perforated.

The following is a description of what I consider the best means of carrying out the invention.

The accompanying drawings form a part of this specification.

Figure 1 is a front view. Fig. 2 is a vertical section on the line 2 2 in Fig. 1; and Fig. 3 is a horizontal section, on a larger scale, on the line 3 3 in Fig. 1.

Similar letters of reference indicate corresponding parts in all the figures where they appear.

A is the front end of the boiler; A', the stack; A², the front connection or uptake, sometimes termed "breeching," and the horizontal dotted line A³ the upper tier of ordinary tubes, (shown simply as a single flue,) which perform the usual function of bringing forward to the front connection the gaseous products of combustion which have moved rearward under the body.

B is a pipe bringing steam from the dome of the boiler, (not shown,) and B' a cock which may control it, but which will usually stand fully open. B² is a "coil" or series of traverses of this pipe through which the steam passes, arranged at the front end of the boiler above the line A³, so that these pipes do not interfere with the cleaning of the tubes. The steam in traversing the coil A³ is superheated.

C is the grate, c the ash-pit space under the grate, and D the ash-pit door, formed with a nearly elliptical casing D' opening through it and turning on hinges D², which may be of the ordinary construction.

E is a swinging joint in the line of the hinges receiving steam from the superheating-coil B² through the descending pipe D³ and delivering it into the nearly elliptical tapering coil or snail M, which covers practically the whole interior of the elliptical casing. Describing the apparatus in the position for blowing the fire, the face of the tapering coil, which in this position is presented toward the interior of the ash-pit, has a single line of small perforations m. There are four or other desired number (shown as about two

and a half) of complete turns or coils of the pipe in the tapering coil. Each turn has straight portions M' M^3 , &c., extending horizontally, and the outer and larger coils have each considerable upright portions M^2 . Each succeeding turn is smaller and set farther inward toward the interior of the ash-pit. The innermost end M^4 is turned, as shown, to extend about in the line of the motion of the air and is screw-threaded and receives a finely-perforated cap N n .

There is in addition to the rarely used cock B' at the higher position a cock D^4 more conveniently reached and which controls the flow of steam from the superheater to the tapering coil. When the door D is shut and this cock is open or partially open, the steam jets inward into the ash-pit from all the apertures m , so that each jet moves past, but does not strike the coil next within that from which it issues. The several jets n from the cap N blow obviously without risk of striking anything. All drive the surrounding atmospheric air inward to induce a plenum in the ash-pit and accordingly to move the air and superheated steam up through the grate to quicken the fire, according as the boiler-pressure is high or low and as the cock D^4 is more or less opened. To obtain access to the ash-pit to remove ashes and clinkers or for any other purpose, it is only necessary to shut the cock D^4 and swing open the door D , carrying the elliptic casing and tapering coil with it. This coil or snail may, with its capped end N , extend well into the ash-pit, taking care not to reach so far that the smallest tapering coil or the casing D will not strike the opposite side of the doorway in opening and closing, and when swung quite open it will simply project outward from the boiler-front and will offer no obstruction to working in the ash-pit. The construction allows so much space for the passage of the air by its motion simply inclining outward from the center line in passing each coil that no appreciable resistance seems to be due to the presence of the pipe, allowing natural draft to be made available when the steam is partly or entirely shut off.

Modifications may be made without departing from the principle or sacrificing the advantages of the invention. I can vary the sharpness of the curves at the corners of the nearly elliptical casing D' and the nearly elliptical tapering coils of the snail. I can vary the diameter of the pipe and the sizes of the perforations, taking care to have such a ratio that the pressure of the steam will be maintained with only slight loss quite to the inner end. The door D may be made to overlap more or less upon the metal of the boiler-front adjacent to the doorway, the main function of the door exterior to the open casing D' being to simply prevent the air in the ash-pit, which is a half-ounce per square inch or some other amount above atmosphere, from

blowing out. The superheating of the steam may be effected at other points than shown. One may be in the back connection. A specially good place is under the boiler in rear of the bridge-wall.

I claim as my invention—

1. As a means for blowing into ash-pits by steam an approximately helical but tapering coil of pipe mounted in an aperture in the wall and connected with a steam-boiler, the several convolutions being perforated on the sides presented toward the interior of the ash-pit and so arranged that the jets of steam projected from each convolution pass on the outer side of each of the smaller convolutions all substantially as herein specified.

2. As a means for blowing into ash-pits by steam-jets, the combination with the swinging joint E , door D and casing D' of a nearly elliptical tapering coil M within said casing D' formed from a single continuous length of pipe having a line of perforations m arranged to project jets from each convolution past the next smaller convolution, all substantially as herein specified.

3. As a means for blowing into ash-pits by steam-jets, the combination with the swinging joint E , door D and casing D' , of a nearly elliptical tapering coil M within said casing D' formed from a single continuous length of pipe having a line of perforations m , arranged to project jets from each convolution past the next, the axially-turned end M^4 and the removable cap N on such end, all adapted to serve substantially as herein specified.

4. As a means for blowing into ash-pits by steam-jets, the combination with the swinging joint E , door D and casing D' , of a nearly elliptical tapering coil M within said casing D' having perforations m , arranged to project the steam from each convolution past the next, and with the drying and superheating coils B^2 arranged in the spent gases and communicating with said coil M through said joint E , all arranged for joint operation substantially as herein specified.

5. The combination with a closed ash-pit provided with an air-inlet passage opening into said ash-pit below the grate, of an air-impelling steam-pipe in said passage in the form of a tapering coil so as to cause little obstruction to said passage and provided with orifices so arranged as to project the steam in jets parallel with the axis of said passage and of said coil and thereby to avoid the interruption of said jets by contact with one another or the inner convolutions of said coil, substantially as described.

In testimony that I claim the invention above set forth I affix my signature in presence of two witnesses.

EDWARD GIBSON.
